UNITED STATES PATENT OFFICE.

WALTER H. STEWART, OF FRANKLIN, NEW HAMPSHIRE, ASSIGNOR TO
MORGAN WRIGHT, OF NORRISTOWN, PENNSYLVANIA.

CIRCULAR-KNITTING MACHINE.

SPECIFICATION forming part of Letters Patent No. 413,101, dated October 15, 1889.

Application filed January 22, 1889. Serial No. 297,155. (No model.)

To all whom it may concern:

Be it known that I, WALTER H. STEWART, of Franklin, in the county of Merrimac and State of New Hampshire, have invented certain new and useful Improvements in Circular-Knitting Machines, of which the following is a specification.

My invention relates to knitting-machines of the circular class organized or equipped for the knitting of complete stockings having round heels and toes; and it is an improvement on the machine shown and described in Letters Patent granted February 5, 1889, No. 397,444.

15 It is the object of my present invention to provide improved means for reciprocating the cam-plate in the operation of knitting heels and toes.

It is also the object of my present invention 20 to provide means whereby the movement of the cam-plate may be automatically changed from rotary motion to reciprocating motion.

It is also the object of my present invention to provide improved means for automatically 25 rendering inoperative a portion of the needles in the circle, as in knitting heel and toe work.

It is also the object of my present invention to provide improved means for automatically stopping the machine at predetermined 30 periods for the purpose of changing the yarn, or for other reasons.

It is also the object of my present invention to provide other improvements incidental to those hereinbefore mentioned.

35 My invention will first be described in connection with the accompanying drawings forming a part of this specification and then pointed out in the claims.

Of the drawings, Figure 1 is a top plan 40 view of my improved knitting-machine. Figs. 1^a and 1^b are diagrams hereinafter more particularly referred to. Fig. 2 is a side elevation of the same. Fig. 3 is a sectional end elevation. Fig. 4 is a bottom plan view of a 45 portion of the cam-plate, showing the needle-operating cams. Fig. 5 is a sectional detail taken on the line 5 5 of Fig. 4. Fig. 6 is a detail view in end elevation of parts shown in Fig. 2. Fig. 7 is a sectional detail of the

clutch-collar and its adjuncts, whereby the 50 movement of the cam-plate is reversed or changed. Fig. 8 is a sectional detail of a part of the mechanism for operating the ratchet-wheels hereinafter referred to. Fig. 9 is a sectional detail view of a portion of the 55 mechanism for stopping the machine at predetermined periods. Fig. 10 is a sectional detail taken through the needle-bed and cam-plate and showing the long needles. Fig. 11 is a sectional detail, similar to Fig. 10, showing 60 the short needles. Fig. 12 is a detail view designed to illustrate the manner of operating the needle-supporting and slide-moving chains by means of the reciprocating rack-bars. Fig. 12^a is a plan view of a pawl at- 65 tached to the chain-blades. Fig. 13 is a detail view designed to show the construction of the chains and attached needle depressing and raising slides. Fig. 14 is a detail view showing a portion of the means for raising 70 the cam for operating the short needles, as when heel and toe work is being knit. Fig. 15 consists of diagrams also showing the manner of raising the cam for operating the short needles. 75

The same letters of reference designate the same parts in all of the views.

Reference is made to the machine shown and described in my hereinbefore-mentioned patent for a full understanding of parts and 80 features of the machine here shown, but not claimed, and hence not herein described in detail.

In the drawings, A is the base of the machine, in which are set pillars B, which support upon their upper ends the needle-bed C, which latter part or device is provided with radial grooves, in which are arranged two sets or series of needles D E, the former being what I term "long needles" and the latter 90 "short needles."

F is the needle-operating cam-plate, arranged to rotate on the needle-bed, and provided on its outer edge or portion with gear-teeth, which are engaged by the teeth of a 95 gear G on the inner end of a shaft H, which shaft is provided with two pulleys I I, turning loosely thereon, and a hand-wheel J. Be-

- tween the pulleys I is a clutch-collar K, splined on the shaft H, so as to turn with the same, but so as to be capable of being moved longitudinally thereon. The pulleys I are provided on their inner sides with holes or recesses adapted to receive spring-pressed pins L in the ends of clutch-collar K when said clutch-collar is moved into contact with either of said pulleys.
- 10 M is the main or driving shaft, provided with a driving-pulley N and two fast pulleys O O, corresponding to pulleys I on shaft H. Pulleys O may be supposed to be belted to pulleys I, one of such belts being straight and the other crossed, so that the direction in which the cam-plate F will be driven will depend upon with which pulley I the clutch-collar K is for the time being connected, it being understood of course that the rotation 15 of the cam-plate may be stopped altogether by moving the clutch-collar K to a position between the pulleys I where the pins L may not engage either.
- 15 P is an arbor vertically supported in suitable bearings and provided on its upper end with a lever or an arm Q, which extends over the cam-plate and in the path of travel of a pin R in said cam-plate. The arbor P is also provided with an arm S, which at its free end 20 engages or enters a groove in clutch-collar K. At its lower end arbor P is provided with a forked arm or finger T. With this construction it will be seen that if arbor P should be rocked in its bearings clutch-collar K would 25 be moved on shaft H, so as to be connected with either of the pulleys I or be disconnected from both.
- 25 U are brackets connected with a stationary part of the machine, provided with ways for 30 supporting and guiding the pawl-carrying blocks V and needle-supporting chains W, one end of which is connected with said block V and the other with the needle depressing and raising slides X.
- 30 Y are rack-bars arranged over the brackets U, and so as to be reciprocated in bearings Z.
- 35 As explained in my aforesaid application, the needle-bed is provided with a circumferential guideway at a point beneath the tails of the long needles, to guide the chains W and 40 slides X, so that the chains may support the tails of said needles, or so that the slides may engage and depress or raise the said needles, as the case may be.
- 45 a, Fig. 12, is a two-armed pawl, (shown in plan in Fig. 12^a.) which pawl is pivoted to the block V, and is operated upon by a spring b, so that when said pawl is moved or 50 adjusted in a manner that will permit of one of its arms engaging the notches of the reciprocating rack-bar Y it will be maintained in such position until moved or adjusted so that the other arm of said pawl will engage the rack-bar.
- 55 c is a bracket or support connected with the brackets U, and upon a stud d, connected with said support, is centrally fulcrumed a

lever e, which lever is pivotally connected with the rack-bars Y. A lever f, Y-shaped at its inner end, is rigidly connected at its outer end with lever e at the fulcrum-point of the latter.

g is a lever arranged beneath the lever f and fulcrumed toward its outer end on the bracket c. Said lever g is broadened at its outer end, on the sides or ends of which broadened part are secured upwardly-projecting pieces or flanges h, with which are connected springs i, extending rearwardly and resting on or near the end of lever f.

j are blocks connected with lever f and arranged to operate between the projecting pieces or flanges h. Both levers f and g are arranged to extend out over the cam-plate and over a ratchet-ring k, supported upon and arranged to turn in a suitable circumferential groove or bearing in the cam-plate. It will now be seen that by moving the inner free end of lever f back and forth the rack-bars Y will be reciprocated in their bearings in opposite directions—that is, one will be moved outward when the other is being moved inward—and that by moving the inner free end of lever g in one direction the corresponding end of lever f will be moved in the opposite direction, the latter lever moving or reciprocating the rack-bars.

l are brackets fastened to the bed of the machine and serving to hold the cam-plate in place and guide it in its rotary movement. In one of these brackets l is arranged a vertically-movable pin m, the manner of moving which and the function of which will presently be described.

n designates a cam on the ratchet-ring k and extending one-half way around thereon, o being a similar cam arranged outside of cam n and extending a little more than half-way around on the ratchet-ring.

p is a short cam on the ratchet-ring k, upon which cam p may rest a pin q, extending laterally inward from one end of a lever r, fulcrumed on a stud s, the other end of which lever r is pivotally connected with the pin R, set in a hole in the cam-plate, a spiral spring t (shown in dotted lines in Fig. 2) being arranged in said hole and serving to press the pin R upward when permitted so to do.

u is a bracket secured to the cam-plate k, and supporting in its outer end a vertically-arranged pin v, which is held pressed downward by a spring w, connected at one end with the bracket u, and engaging at its other end the pin v, as shown in Fig. 5.

x is a bracket similar to bracket u, and supporting a pin y, which is normally held down by a spring z. Pin v is arranged to travel over cam n and pin y over cam o in the rotation of the ratchet-ring k.

a' is a lever pivoted at its inner end to the cam-plate F and having its free end extended out over the brackets l, a spring b', coiled around the pivotal stud of said lever and having one end fastened to the latter and the

other end secured to the cam-plate, serving to hold the lever in a radial position with respect to the axis of the cam-plate.

5 *c'* is a pawl pivoted to lever *a'* and held by means of a spring in engagement with the teeth of ratchet-ring *k*.

10 *d'* designates the yarn-carrier, secured to the cam-plate, and *e'* is a ring having a limited reciprocating movement on the cam-plate, to 15 which ring is secured the sinker-operating cam *f'*, which devices have the usual functions and operate in well-known ways.

23 4 5 6 7 designate the needle-operating cams, the long needles being projected and 15 retracted by the cams 2 4 6 and the short needles moved in like manner by the cams 3 5 7. Cams 2 3 are secured to the slide *g'*, operating radially in the cam-plate, and cams 6 7 are secured to a similar slide *h'*, this construction and arrangement of parts being for the 20 purpose of adjusting the cams to regulate the throw of the needles. The slides *g'* and *h'* are secured in position in the cam-plate by means of set-screws *i'* *j'*, Fig. 1.

25 *k'* designates a block which passes through bracket *u*, and is provided on its outer end with a rounded stud *l'*. This rounded stud of the block *k'* is arranged to rest against the inner edge of the ratchet-ring *k* and to operate in a cam-slot *m'*, formed by a notch made in the ratchet-ring, and a cam *n'*, attached to the cam-plate. (See Fig. 14.) *o'* designates a block, the upper end of which is pivotally connected with the inner end of block *k'*, said 30 block *o'* passing down through a hole in the cam-plate and a slot in the inner end of an angular block *p'*, to which latter device said block is pivotally connected, cam *o* being rigidly secured thereto. (See Fig. 15.)

40 Sufficient description has already been given for explanation as to how the operation of the cam-plate may be changed from a rotary motion, as when a tubular web is being knit, to a reciprocating motion, as when heel and toe 45 work is being performed, and as to how the operation of the needles may be controlled.

The parts being in the position in which they are represented in Fig. 1, the pin *m* is raised, (this being accomplished automatically 50 by means to be presently described,) the cam-plate continuing to revolve in the direction of the arrow, Fig. 1, as before, until the end of lever *a'* strikes and passes pin *m*, which will result in moving ratchet-ring *k* around 55 on the cam-plate the distance of one tooth of said ring. This movement of the ratchet-ring effects three changes, which may be described as follows: first, cam *p* is carried from under pin *q* of lever *r*, permitting pin *R* to be 60 raised by the spring *t* thereunder; second, pin *v*, held down on the face of the ratchet-ring *k* by spring *w*, will be raised by cam *n* passing thereunder; third, the rounded end or stud *l'* of block *k'* will pass out of the angular 65 cam-slot *m'*, formed between cam *n'* and the notch in the ratchet-ring, onto the inner edge

of said ratchet-ring, moving cam-block *k'* inwardly and through the medium of blocks *o'* and *p'* raising cam *o*, so that said cam will not act upon the shanks of the short needles, 70 thus rendering said needles, which may be supposed to comprise one-half of the needles in the circle, inoperative. It is to be understood that the parts are so timed as to effect these changes at a time when and place where 75 the needle-operating cams are over and acting upon the long needles, so that when the cams reach the short needles they will not affect them in any way. Pin *R*, being raised to such height as to cause it to engage the lever *Q* in the rotation of the cam-plate, strikes and moves said lever, shifting clutch-coilar *K* through the medium of arbor *P* and arm *S*, disengaging said clutch-collar from one pulley *I* and connecting it with the other, and so 80 reversing the course of movement of the cam-plate. As the cam-plate moves around in a direction opposite to the arrow, Fig. 1, the pin *v*, which was raised after it had passed the lever *f*, now, while moving in the direction of 85 the arrow, enters the *Y* in said lever and moves it to one side, moving one rack-bar *Y* outward and the other inward, the outward-moving rack-bar moving the chain *W*, with which it co-operates, out through the medium of the 90 pawl attached to its block *V* a distance sufficiently far to cause the connected slide *X* to depress one of the long needles, and the inward-moving rack-bar moving to an extent 95 sufficient to cause the pawl on the block of 100 its co-operating-chain to engage an advanced notch in the rack-bar. The cam-plate continuing to revolve in a direction opposite to the arrow, Fig. 1, pin *R* will be brought again into contact with lever *Q*, effecting a reversal 105 of the direction of movement of the cam-plate and the movement of the lever *f* by pin *v* in a direction opposite to that it was before moved, and this operation will be kept up until ratchet-ring *k* will have been turned substantially one-half-way round, when pin *v* will ride off of cam *n* onto the face of ratchet-ring *k*, at which instant pin *y* in bracket *x* will ride up onto cam *o*. Simultaneously with this operation the arm of each pawl on the pawl-carrying blocks *V* which is engaged with the teeth or notches of the rack-bars will be 115 brought into engagement with a lug *g'* on the side of the rack-bar, with the effect of reversing the position of said pawls, so that further 120 reciprocating motion of the rack-bars will result in moving the chains back or inward and raising a needle at each inward movement. The operations will continue as before, excepting that lever *f*, instead of being moved by 125 the operation of pin *v* thereon, will be moved through the medium of lever *g*, acted upon by pin *y* on cam *o*. The reason for this change in the manner of operating lever *f* is for the purpose of effecting the raising or bringing 130 into operation of a needle after it has been passed by the needle-operating cams and

just before the cam-plate is reversed in its movement, and so, as it were, wrapping the yarn around the added needle, in order to effect "close joinings" along the line where 5 the needles are thrown out of and brought into operation. For a fuller understanding of this operation and its effects particular reference may be had to Figs. 1^a and 1^b. When the new or added needle 23 is brought into action before the yarn-guide and needle-operating cams reach the same, the yarn will be laid upon such needle, as shown in Fig. 1^a, and when said new or added needle 23 is not brought into operation until after the yarn-guide and needle-operating cam have passed the same, but before the cam-plate is reversed, such new needle will be projected over the yarn, so that as it comes back the yarn will be laid upon and wrapped around the needle 15 23, as shown in Fig. 1^b. The result, in the first instance, would be to leave eyelet-holes, so called, while in the latter instance close joinings will be effected. After the ratchet-ring has effected a complete revolution, and 20 25 is brought into the position in which it is represented in Fig. 1, it may be supposed that chains W will have been moved fully inward by the action of the rack-bars upon their attached pawls, the rounded part l' of block k' 30 35 will have been acted upon by cam n' to depress cam 5 through the medium of the described intermediate devices, pins R, v, and y will have been depressed, pin m drawn down, and the knitting of a heel or toe completed, when the cam-plate will be revolved to effect the knitting of tubular work. Upon the chains being moved fully in, as before explained, the arms of the pawls a in engagement with the teeth or notches of the rack-bars will be brought into contact with lugs 40 45 similar to lug 83, on the opposite sides of the rack-bars, with the effect of reversing the position of the pawls, or, in other words, moving the pawls to their first-mentioned position.

The means whereby pin m is automatically raised will next be explained.

On shaft H is a pinion a'', meshing with and operating a gear b'', supported on a stud 50 55 connected with a bracket f'', attached to the frame of the machine, which gear b'' is provided on one side with a cam c'' and on the other side with a cam d''.

e'' designates a lever pivoted to the bracket f'', which lever is provided on its free end with a bowl g'', arranged to rest upon the cam c'', and it may be held thereagainst by a spring e'''. To the free end of lever e'' is pivoted a pawl h'', which rests upon the 60 65 ratchet-wheels i'' j'', the former of which is fast on the arbor k'', while the latter turns loosely thereon. To one side of the ratchet-wheel j'' is secured a sprocket-wheel l'', carrying an endless chain m'', provided with a laterally-projecting pin n''. Secured to arbor k'' and alongside of sprocket-wheel l'' is a

disk o'', provided on its periphery with a radially-projecting pin p'', which pin p'' is adapted in the revolution of chain m'', to be engaged by the laterally-projecting pin n'' 70 on the chain, and so carry said disk and ratchet-wheel i'' around therewith. Secured to the opposite end of arbor k'' is a disk q'', having a notch or depression r'' in its periphery, and upon this disk rests the free end of 75 a lever s'', provided with a toe or projection t'' at the point where it rides on the disk q''. u'' is a rod or strip connecting pin m with lever s''. It will now be understood that when the toe t'' of lever s'' rests in the notch or depression r'' of disk q'' pin m will be drawn down; but when disk q'' is revolved, so as to bring the toe t'' on the highest part of the periphery of said disk, the pin m will be raised, and to properly time the operation of disk q'' is the purpose of the mechanism just previously described.

Ratchet-wheel i'', having one tooth cut away, as shown at v'', Fig. 8, will not be operated by the pawl h'' when it reaches said 80 mutilated tooth, and consequently arbor k'' will not be moved. Ratchet-wheel j'', to which is attached sprocket-wheel l'', will, however, be moved around on arbor k'' and eventually bring the pin n'' of chain m'' into 85 contact with pin p'' of disk o'', and so move arbor k'' and ratchet-wheel i'' that pawl h'' will catch into the whole teeth of the same and so move said ratchet-wheel i'', arbor k'', and disk q''. 90 95 100

It is of course understood that instead of providing means for automatically raising pin m said pin might be raised and lowered by hand, and, indeed, all of the pins connected with or operated by the ratchet-ring k may 105 be placed in operative position, removed, or adjusted by hand.

a''' designates a disk secured to arbor k'', which disk is provided on its periphery with cams b''' and c''', and d''' designates an angular lever fulcrumed on a stationary part of the machine, and extending around the gear b'' and outward toward or over the disk a'''. A slide e''' is arranged beneath lever d''', so as to have a limited movement thereunder, slots f''' being for this purpose formed in said lever, and the shanks of headed screws g''' passed through said slots and screwed into the slide. 110 115 120

h''' designates a lever fulcrumed at i''' to the side of the slide and provided at its forward end with a laterally-projecting pin j''', which rests upon the periphery of the disk a'''. The opposite end of lever h''' is notched to adapt it to engage a pin k''' on the end of 125 lever d''' and hold the slide e''' out against the stress of a spring l''', one end of which is connected with the lever and the other with the slide.

When the arbor k'' is revolved, the disk a''' 130 will be operated in like manner until one of the cams b''' or c''' is brought into contact

with the pin j''' of lever h''' , when said lever will be moved on its fulcrum so as to disengage its notched end from pin k''' of lever d''' , allowing the spring l''' to move the slide e''' 5 inward to a position where it will be struck by cam d'' in the rotation of gear b'' , moving the lever h''' to one side, as from the full to the dotted line position, Fig. 9, by which operation the pin m''' in said lever, acting 10 upon the inclined sides of the forked end of arm or finger T , will move said arm to the position in which it is represented in said last-mentioned figure, the result of which will be to operate arbor P , so as to cause arm S to 15 move clutch-collar K to a position intermediate of the pulleys I I and disengage it from both, thus stopping the machine. This stopping of the machine is desirable at times, as when the knitting of a heel or toe is to be 20 commenced and when such work is completed, the cam b''' being for the first-mentioned purpose and cam c''' for the latter.

It is obvious that various changes may be made in the form and arrangements of parts 25 comprising my improvements without departing from the nature or spirit thereof.

Having described my improvements, I declare that what I claim is—

1. The combination, with the needle-bed 30 and needles D E , of the cam-plate provided with needle-operating cams 2 3 4 5 6 7, ratchet-ring k , supported on the cam-plate and provided on its inner edge with a notch, cam n' , block k' , provided with the stud l' , adapted 35 to rest against the inner edge of the ratchet-ring and be operated by said cam n' , connections, substantially as set forth, between block k' and cam 5 , and means for operating the cam-plate and ratchet-ring, as set forth.

40 2. A rotary cam-plate, a needle-bed, two sets of needles D E , the former set provided with extensions or tails, movable chains supported by the bed and adapted to form a support for the tails of the needles, grooved or 45 slotted slides attached to the said chains to engage the tails of said needles to lower or depress the same, brackets upon which said chains may be moved and guided from and to the bed, a pawl connected with each of said 50 chains, rack-bars for engaging said pawls, lever e , connected with said rack-bars, lever f , connected at its outer end with lever e and extending over the cam-plate, lever g , fulcrumed upon said bracket, pivotally connected 55 with lever f , and also extending over the cam-plate, a ratchet-ring arranged on the cam-plate and provided with cams n o , means for moving said ratchet-ring, pins arranged to travel on said cams and on the face of the ratchet-ring, and springs for pressing said pins downward, as set forth.

5. The combination, with the needle-bed, 95 needles, and cam-plate, of a ratchet-ring on said cam-plate, a lever pivoted upon the cam-plate and provided with a pawl to engage the ratchet-ring, a vertically-movable pin m 100 to engage and move said lever, a rotary arbor, a cam on said arbor, a lever resting on said cam, a connecting-bar between said last-mentioned lever and pin, whereby the latter may be raised and lowered, a driving-shaft, 105 and connections between the driving-shaft and cam-plate and between the driving-shaft and rotary arbor, whereby they may be operated, as set forth.

6. The combination, with the needle-bed, 110 needles, and cam-plate, of a ratchet-ring on said cam-plate, a lever pivoted upon the cam-plate and provided with a pawl to engage the ratchet-ring, a vertically-movable pin m to engage and move said lever, a rotary 115 arbor, a cam on said arbor, a lever resting on said cam, a connecting-bar between said last-mentioned lever and pin, ratchet-wheel i'' , having one tooth cut away, secured to said arbor, ratchet-wheel j'' , loose on said arbor, 120 sprocket-wheel l'' , secured to ratchet-wheel j'' , chain m'' on said sprocket-wheel, and provided with the pin n'' , disk o'' , provided with pin p'' , fast on said arbor, a pawl engaging said ratchet-wheels, a driving-shaft, and connections between said driving-shaft and cam-plate and between the driving-shaft and pawl for operating the same, as set forth.

7. The combination, with needle-bed, needles, and cam-plate, of a rotary arbor H , a gear connecting said arbor with said cam-plate, pulleys I I , loose on said arbor, a clutch member splined on said arbor to be moved longitudinally thereon but to 130 rotate therewith, arms or levers Q S and their arbor P , a ratchet-ring on the cam-

plate, and means for moving it, a cam on said ratchet-ring, a lever r , fulcrumed on the cam-plate and provided on one end with a pin resting on said cam and connected at the 70 other end with a vertically-arranged pin, and a spring for pressing said vertically-arranged pin upward, as set forth.

4. A rotary cam-plate, a needle-bed, two sets of needles D E , the former set provided 75 with extensions or tails, movable chains supported by the bed and adapted to form a support for the tails of the needles, grooved or slotted slides attached to the said chains to engage the tails of said needles to lower or 80 depress the same, brackets upon which said chains may be moved and guided from and to the bed, a pawl connected with each of said chains, rack-bars for engaging said pawls, lever e , connected with said rack-bars, lever 85 f , connected at its outer end with lever e , and extending over the cam-plate, lever g , fulcrumed upon said bracket, pivotally connected with lever f , and also extending over the cam-plate, a ratchet-ring arranged on the cam- 90 plate and provided with cams n o , means for moving said ratchet-ring, pins arranged to travel on said cams and on the face of the ratchet-ring, and springs for pressing said pins downward, as set forth.

5. The combination, with the needle-bed, 95 needles, and cam-plate, of a ratchet-ring on said cam-plate, a lever pivoted upon the cam-plate and provided with a pawl to engage the ratchet-ring, a vertically-movable pin m 100 to engage and move said lever, a rotary arbor, a cam on said arbor, a lever resting on said cam, a connecting-bar between said last-mentioned lever and pin, whereby the latter may be raised and lowered, a driving-shaft, 105 and connections between the driving-shaft and cam-plate and between the driving-shaft and rotary arbor, whereby they may be operated, as set forth.

6. The combination, with the needle-bed, 110 needles, and cam-plate, of a ratchet-ring on said cam-plate, a lever pivoted upon the cam-plate and provided with a pawl to engage the ratchet-ring, a vertically-movable pin m to engage and move said lever, a rotary 115 arbor, a cam on said arbor, a lever resting on said cam, a connecting-bar between said last-mentioned lever and pin, ratchet-wheel i'' , having one tooth cut away, secured to said arbor, ratchet-wheel j'' , loose on said arbor, 120 sprocket-wheel l'' , secured to ratchet-wheel j'' , chain m'' on said sprocket-wheel, and provided with the pin n'' , disk o'' , provided with pin p'' , fast on said arbor, a pawl engaging said ratchet-wheels, a driving-shaft, and connections between said driving-shaft and cam-plate and between the driving-shaft and pawl for operating the same, as set forth.

7. The combination, with needle-bed, needles, and cam-plate, of a rotary arbor H , a gear connecting said arbor with said cam-plate, pulleys I I , loose on said arbor, a clutch

member splined on said arbor to be moved longitudinally thereon but to rotate therewith, arbor P, and its arms S T, gears a'' and b'' , the latter provided with cam d'' , arbor k'' , 5 and means to rotate it from gear b'' , disk a''' , provided with cams b''' c''' , lever d''' , provided with pin m''' , spring l''' , slide e''' , and lever h''' , as set forth.

In testimony whereof I have signed my name to this specification, in the presence of two 10 subscribing witnesses, this 10th day of January, A. D. 1889.

WALTER H. STEWART.
